INVENTOR:

Michael H. Wright

MICHAEL H. WRIGHT, OF CHICAGO, ILLINOIS.

Letters Patent No. 61,909, dated February 5, 1867; antedated January 25, 1867.

GRAIN DRIER.

The Schedule referred to in these Letters Patent and making part of the same:

TO ALL WHOM IT MAY CONCERN:

Be it known that I, MICHAEL H. WRIGHT, of Chicago, in the county of Cook, and State of Illinois, have invented a new and useful Improvement in Grain Driers; and I do hereby declare and make known that the following is a full, clear, and exact description of the same, reference being had to the accompanying drawings, and the letters and figures marked thereon, which form part of this specification.

My invention relates to a grain-drying apparatus having a series of one or more hollow, revolving cylinders, arranged one above another, through which the grain passes in succession from the upper to the lower one of the series as hereinafter more fully described, and it consists in passing the fire-flue of the furnace connected with said apparatus through the said cylinders, substantially as hereinafter described. My invention further consists in a novel arrangement of buckets upon the interior surfaces of the cylinders aforesaid, which carry the grain up to the upper part of the cylinder, and then discharge it upon the central shaft heated by the flue aforesaid, as is hereinafter set forth.

To enable those skilled in the art to construct and use my invention, I will proceed to describe its construction and operation with particularity, making reference in so doing to the drawings aforesaid, in which—

Figure 1 represents a side elevation of my invention.

Figure 2. a longitudinal vertical central section thereof; and

Figure 3. a transverse section of the same at x in fig. 1.

Similar letters of reference in the several figures indicate the same parts of my invention.

A represents any suitable frame to support the operating parts of my invention, which may be enclosed or not, as preferred. B represents a series of cylinders, arranged one above another, as shown, and having a longitudinal inclination in opposite directions, sufficient to cause the grain to pass from one end to the other, as desired. The said cylinders are attached to a hollow shaft, C, by means of the arms a, as shown, or in any other suitable manner, said shafts being supported at each end upon suitable frictional bearings or wheels, D, upon the cross-supports A at the ends of the frame, as shown. The ends of the said cylinders are closed by stationary heads marked B', which are permanently secured to the frame, the cylinders revolving closely against said heads, there being suitable openings at the centre thereof to allow the hollow shafts to pass through, as shown. The ends of the arms a which are attached to the cylinders are bent back, as shown in fig. 3, and a long strip, b, is attached thereto, forming a shelf or series of shelves or buckets, upon which the grain is carried up as the cylinders revolve, near the top, whence it is precipitated upon the hot shaft C, heated as hereinafter set forth. The required rotatory movement is given to said cylinders by means of the gear-wheel F, upon the shaft E, which is revolved by belting upon the drum G, and the spur-wheels H I, upon said hollow shafts C, or in any other suitable and convenient manner. J represents a suitable furnace, having a system of hot-air pipes, M, into which the air is forced by any suitable fan or blower, and when heated passes into the cylinders B, through suitable openings in the heads thereof, to receive the hot-air pipes. L represents the fire and smoke flue or draught passage of the furnace, and it is first passed through the aforesaid hollow shaft C of the lower cylinder, whence it passes in like manner through the shaft of the next cylinder, and so on through the entire series, passing from the upper cylinder into a suitable smoke stack or chimney, as desired. By this arrangement, in addition to the heat produced by the hot-air pipes, the entire heat from the fire is made available for heating and drying purposes, thus producing an apparatus for drying grain at once cheap, simple, and economical.

The grain is introduced into the higher end of the upper cylinder, where more than one is used, through a spout, S, and passes out at the opposite end through a suitable opening, as shown, in the head, whence it falls through a suitable hopper, formed upon the head of the cylinder, below into said cylinder, and so on through the series, the grain during its entire progress through the machine being many times carried up upon the shelves aforesaid, marked b, and dropped and scattered down through the heated air in the cylinder, upon the revolving heated shaft C, whereby it is thoroughly scattered and separated so as to greatly facilitate the process of drying the same.

Having described the construction and operation of my invention, I will now specify what I claim, and
desire to secure by Letters Patent:

I claim passing the fire flue of a furnace through a series of revolving cylinders, in a grain-drying apparatus, arranged and operating substantially as herein specified and shown. MICHAEL H. WRIGHT.

MICHAEL H. WRIGHT.
